his Atty.

UNITED STATES PATENT OFFICE.

JOHN J. RICHARDS, JR., OF BROOKLINE, MASSACHUSETTS.

RESERVE PROVIDER FOR FUEL TANKS.

Application filed February 11, 1920. Serial No. 357,854.

To all whom it may concern:

Be it known that I, JOHN J. RICHARDS, Jr., a citizen of the United States, and resident of Brookline, county of Norfolk, Commonwealth of Massachusetts, have invented an Improvement in Reserve Providers for Fuel Tanks, of which the following description, in connection with the accompanying drawings, is a specification, like characters 10 on the drawings representing like parts in each of the several views.

This invention relates to devices for the delivery of gasoline or a like liquid fuel from liquid tanks as commonly employed 15 in the suction or vacuum feed system of automobiles. A principal object of the invention is to provide a convenient, simple, and reliable device adapted for feeding out the gasoline from a tank down to a given point 20 only and capable of being then set to deliver the remainder of the contents of the tank as an emergency or reserve supply that is thus available to the driver after he has been warned by the exhaustion of the normal supply 25 of the tank. More specifically the invention includes in a preferred form, a construction and arrangement including outer and inner relatively slideable members so arranged that when a projecting handle or 30 connection in the top of the device is pressed downward or inward the device is set for normal conditions, i. e., so that the delivery will stop before the reserve supply is fed out and so that upon a drawing upward or 35 outward of the handle or connection the device is set for making the reserve supply available. More broadly the invention comprehends the employment of relatively movable inner and outer tubes adapted to set the 40 device either for preserving the reserve supply or making the same available by a single, or one-way movement of the handle or operating connection. The foregoing and other objects and advantages of the invention will 45 more fully appear from the following detailed description, and the distinctive features of novelty will be pointed out in the appended claims.

Referring to the drawings:

50 Fig. 1 is an elevation showing my improved device in one embodiment thereof, the delivery head being shown in section;

Fig. 2 is an enlarged fragmentary elevation illustrating the control of the fuel inlet 55 in the form of Fig. 1;

Fig. 3 is an elevation with a mounting

block therefor in section, showing another form of the device, an intermediate portion being broken away.

Fig. 4 is an elevation showing the device 60 of Fig. 3 mounted in a fuel tank, the tank being shown in section.

Fig. 5 is a fragmentary detail view partly in elevation and partly in section showing on a larger scale the means for holding the 65 delivery tube in adjusted position in the device of Fig. 3; and,

Fig. 6 is a fragmentary detail elevation at right angles to Fig. 3 and showing the fuel intake portion of the tubes. 70

Referring to Figs. 1 and 2, 10 indicates a bushing head adapted to be fitted into the top of the fuel tank, for this purpose having a threaded nipple 11 in the lower end thereof and having another threaded nipple 12 75 extending from one side thereof for a connection to the fuel delivery tube. The nipple 11 of the head has fixed by soldering or otherwise in depending relation therefrom, an outer tube 13 which is made of a length to 80 extend substantially to the bottom of the tank. This tube may have a suitable notch or aperture 13^a at its lower end so that the inflow thereto would not be stopped by its contacting on the bottom of the tank. Slid- 85 ably fitted through this outer tube 13 is an inner tube 14 which has an aperture 15 in the upper portion thereof opening into a recess or clearance space 16 there-around in the head 10, which space communicates with 90 the passage through the nipple 12. The upper end of the tube 14 is equipped with a hand-piece 17 which projects above a packing box 18 which is set into a recess at the top of the head 10. It will thus be noted that 95 the tube 14 constitutes a combined controller member and fuel conduit dispensing with the need of any separate operating rod or member, while the outer tube 13 serves as a casing or housing for the inner tube and 100 also to co-operate therewith for preserving or utilizing a reserve supply of fuel, as will be explained. The packing box 18 may consist of a block of cork or like substance adapted both for packing and for friction- 105

ally engaging the tube 14 so as to hold the same in any position to which it may be adjusted. The tube 14 may also be equipped with a stop pin 19 to prevent the same from being drawn out too far. The lower portion 110 of the outer tube 13 is slotted or cut away as indicated at 20 at a distance above the lower

end thereof which is determined by the amount of reserve supply of gasoline which it is desired to preserve. The inner tube 14 is formed with a cut away portion 21 near 5 its lower end, that, when it is in lowered position registers with the cut away portion 20 of the outer tube and thus when the hand-piece 17 is pressed down as shown, the suction will be broken and the delivery of gasoline stopped when the level thereof reaches these registering openings 20, 21. Upon lifting the hand-piece 17 and raising the tube 15 so that the cut out portion 21 is above and out of register with the cut out 20 as 10 seen in Fig. 2, the break in the inner tube constituted by this cut out portion is bridged and covered by the outer tube so that the liquid fuel will then be drawn out until it reaches the level of the bottom of the outer tube, i. e., substantially the entire contents of the tank. This form of the invention is adapted for fuel tanks of automobiles such as, found, for example, in the current type of Hudson cars. In the form of the invention shown in Figs. 3 and 4, a tubular bushing 22 adapted to be fitted into the top 15 of the tank and constituting a mounting for the movable tube member is provided. This block has fitted thereto and secured by soldering or the like an outer depending tube 23 adapted to extend to the bottom of the fuel tank. This tube has well towards its lower end, at the height determined by the reserve supply desired, a cut out portion 24 20 which may be from opposite sides of the tube as seen in Fig. 6 and leaving only relatively narrow webs 24^a holding the lower extension of the tube. Within this tube is fitted for sliding movement an inner tube 25 25 equipped at its upper projecting end with an L connection 26 to the fuel delivery conduit, this L connection constituting also a handle for adjusting the inner tube. In this case the inner tube is shown as terminating just below the cut out portion 24 when said 30 tube is in lowered position as indicated at 25^a, thus in this position the cut out portion 24 is bridged and the two tubes constitute a continuous suction conduit to the bottom of the tank. Upon drawing the inner tube outward a small distance however, its end 25^a is elevated past the cut out portion 24 so that the suction is here broken and the fuel will not be delivered below this level; thus in this 35 form with the inner tube in elevated position the reserve supply is preserved, while when it is pressed down as shown in Fig. 3 the reserve supply is available. For holding the inner tube in either of these positions it may be equipped with spaced apart grooves 27, 28, selectively engageable by a spring 29 housed in a recess therefor in the bushing 22. The lower one 28 of these grooves is preferably provided with a square shoulder at its 40 lower side which serves as an abutment en-

gaging the spring 29 and positively holding the tube against further withdrawal while the other side of such groove is beveled as is also the side of the groove 27 so that the tube may be yieldingly pressed into either of its 70 adjusted positions. This form of the device is adapted for the fuel tanks of cars such as the current Dodge type. It is to be understood that while I show the form in Fig. 1 with an arrangement of the vent or suction 75 control at the lower part thereof adapted for the suction to be broken by a pressing down of the inner tube, and in Fig. 3 show the device as adapted for breaking the seal upon lifting the inner tube, that these particular 80 combinations and relative arrangements are merely illustrative and that the top head portion of the device of Fig. 1 may be associated with the type of vent control of Fig. 3 or vice versa. In these as well as other respects, the forms of the invention shown are to be understood as merely illustrative and not restrictive and reference is therefore had to the following claims rather than to the foregoing description to indicate the scope 85 of the invention.

Having described my invention, what I claim as new and desire to secure by Letters Patent is:

1. A reserve provider for fuel tanks comprising an outer casing tube leading downward through a fuel tank substantially to the bottom thereof with an opening therein relatively near its lower end, and an inner tube constituting a combined controller 95 member and fuel conduit extending from a point external of the tank top downward to said opening, said inner tube fitted for endwise movement within the outer tube and equipped to control the opening therein, whereby in one position of adjustment of such inner tube it constitutes in combination with the outer tube, a continuous delivery conduit from the bottom of the tank, and in another position terminates such conduit at 100 a point substantially above the tank bottom.
2. A device of the kind described comprising a fuel tank having an outer tube casing leading downward from its top substantially to its bottom, and an inner tube slidably fitted for endwise movement therein constituting a combined controller member and fuel conduit, said inner tube extending from a point external of the tank downward to a point in proximity to the tank bottom, said 115 tubes having cooperatively arranged openings therein relatively near the lower ends thereof, arranged and adapted in one position of said inner tube to constitute a continuous delivery conduit for fuel from the bottom of said tank, and in another position to constitute a delivery conduit down to a predetermined point only in said tank.
3. A reserve provider for fuel tanks comprising an outer casing tube mounted in a 120

fuel tank and leading downward substantially to the bottom thereof with an opening therein spaced above its lower end, and an inner tube fitted to slide endwise in said outer tube, said inner tube extending from the tank top to said opening of the outer tube and arranged so that in an elevated position it bridges said opening in said outer

tube to constitute a continuous delivery conduit from the bottom of the tank, and in a lowered position exposes said opening so that such conduit terminates at that point.

In testimony whereof, I have signed my name to this specification.

JOHN J. RICHARDS, JR.
